HERBERT H. CUMMINGS AND ARDEN J. MUMMERT, OF ST. LOUIS, MISSOURI,
ASSIGNORS TO MCQUAY-NORRIS MANUFACTURING COMPANY, A CORPORA-
TION OF MISSOURI.

PATTERN-DRAWING MACHINE.

1,313,882.

Specification of Letters Patent. Patented Aug. 26, 1919.

Application filed October 3, 1918. Serial No. 256,748.

To all whom it may concern:

Be it known that we, HERBERT H. CUMMINGS and ARDEN J. MUMMERT, citizens of the United States, residing at St. Louis, 5 State of Missouri, have invented certain new and useful Improvements in Pattern-Drawing Machines, of which the following is a full, clear, and exact description, reference being had to the accompanying drawings, 10 forming a part hereof.

As well understood in the molding art, the drawing of the pattern from the mold is usually accomplished either by manually tapping the pattern directly with a suitable hammer or tool or indirectly through a bar or rod connected to the pattern, or by subjecting the pattern to a series of tremors or vibrations through the instrumentality of a pneumatic, electric, steam, or other hammer 15 mounted on the frame holding the pattern, either of these methods serving to loosen the pattern from the mold formed by the sand in which the pattern is embedded, after 20 which the pattern is free to be drawn from the mold without disturbing the sand around the impression left by the pattern, and hence without disturbing the design formed in the sand. The drawing of the pattern thus loosened unless large and heavy, is 25 usually accomplished by hand, especially in the case of small castings. Theoretically the pattern should be lifted from the mold or the mold from the pattern by a movement which shall cause a separation of the members 30 at all points along lines at right angles to the parting plane or plane of contact between the members. Such a movement can not be practically accomplished by hand, and so far as we are aware it has never been 35 accomplished mechanically. One of the objects of the present invention therefore is to construct a machine or apparatus in which the drawing of the pattern from the mold may be accomplished by a relative separating movement of translation between the 40 members, the pattern, in the present embodiment of our invention, being preferably the stationary member, and the mold the movable member, though a stationary mold and a movable pattern or an apparatus in which 45 both the pattern and the mold are movable 50 within the scope of our invention.

With the use of our device the preliminary loosening of the pattern from the mold referred to above is not necessary, though of course there may be occasions in practice where such loosening step might be desirable. This feature however is not concerned with our invention which is directed solely to the apparatus by which the drawing of the pattern from the mold is effected. It is obvious that in order to draw a pattern which is stationary, from a mold which is movable, by a movement which shall insure against possible disturbance of the sand around the pattern, the moving mold must not be permitted to suffer any lateral or angular displacement either at the instant of or during the separation of the members, but must be so moved and guided as to strictly preserve a true motion of translation from the contact plane between the members. It is therefore one of the objects of our invention to construct an apparatus in which such a movement shall be assured for the mold and the flask supporting the same, and this by means of a structure which shall be simple, positive in its action and reliable, one containing a minimum number of parts, and one possessing further and other structural advantages better apparent from the following detailed description of the invention in connection with the accompanying drawings in which—

Figure 1 represents a front elevation of the machine showing the flasks and lifting spider therefor in their depressed position, parts being broken away; Fig. 2 is a vertical longitudinal middle section (with parts left in elevation) showing the spider elevated sufficiently to lift the flasks from the pattern plates; Fig. 3 is a top plan of the machine with one of the flasks and its pattern plate removed to expose the table or platform to which the pattern plate is secured; Fig. 4 is a horizontal section on the line 4—4 of Fig. 1; Fig. 5 is a vertical cross-section on the line 5—5 of Fig. 1; Fig. 6 is a vertical section through two superposed flasks and their molds taken on a diagonal corresponding to the line 6—6 indicated in Fig. 3; Fig. 7 is a bottom plan of a portion of one of the molds showing the impression left by the pattern; Fig. 8 is a bottom plan

of the cam ring interposed between the lifting spider and the operating lever; and Fig. 9 is an elevation of the cam ring.

Referring to the drawings, B represents a base plate, the same being provided at the corners with the posts or standards S, and forming with said standards, a suitable supporting frame for the remaining portions of the machine. Screwed, or otherwise secured to the tops of the standards S is a table or platform 1 to which are in turn fastened (by means of screws or otherwise) the pattern plates 2, 2, the two plates being disposed symmetrically about the center of the platform 1 and being substantially square in shape with diagonal corners to match the corresponding corners of the platform 1. To the pattern plate (both plates being alike) are secured the patterns a, those in the present example being patterns of piston-rings disposed symmetrically about the center of the plate, each ring being provided with a riser h, and the several rings connected to a center sprue pin t by means of runners or gates m radiating from the sprue pin to the several rings, as well understood in the art. Adapted to be deposited on each pattern plate is a mold-flask 3 the ribs d of which are so disposed as to come between the pattern rings a when the flask is deposited on the plate (Fig. 3). The flask is square in shape with rounded corners, two pattern plates and two flasks entirely covering the platform or table 1 as clearly obvious from the drawings. As well understood in the art, after the flasks are deposited on the pattern plates, a sand-frame f is placed on top of the flasks, and the sand s is then poured into the flasks and frame on top of the pattern plates, and, by means of a "strike-off" or equivalent tool, is evened off with the upper edge of the sand-frame and top of the sprue pin (the top of the sprue pin coming even with the upper edge of the sand frame). The sand is then pressed or squeezed against the pattern by means of a cope-board c which may be forced against the sand by hand or by any suitable mechanical squeezer, the cope-board being provided with an opening or tubular passage-way o to accommodate the sprue pin t (Fig. 1). The cope-board is driven into the sand frame until the sand has been compacted sufficiently to bring its upper surface substantially even with the top of the flask, this squeezing of the sand causing the pattern to impress itself into the sand, leaving a mold as shown in Fig. 7, the depressions a', h', and m' of the mold corresponding to the raised portions a, h, and m of the pattern, and the sprue hole o' corresponding to the hole left by the sprue-pin t or to the hole o in the cope-board. In Fig. 6 are shown two superposed flasks with their molds, ready for the casting operation, the molten

metal being poured into the top sprue hole o', the superposed sprue holes of the several molds, forming a pouring channel from which the metal finds its way into the several patterns through the gates m', the risers h' taking care of all excess metal and floating impurities, and, by reason of the comparatively large quantity of metal held by said risers, preventing a too sudden chilling of the metal in the pattern molds a', the heat from the metal in a riser being communicated to the metal in the mold a'. So too, the heat from the metal in the several risers h' offsets that from the metal in the sprue pouring channel and gates m', permitting all parts of the metal forming the casting to cool uniformly. Formed on the front and rear walls of the flask 3 are lobes or lugs 4 perforated to loosely receive suitable guide pins 5 projecting from substantially corresponding lugs or lobes 6 on the front and rear walls of the platform 1; and formed at the corners of the flask are diagonally projecting lugs 7 for a purpose to presently appear.

In the present embodiment of the invention, the plate B and table or platform 1 are connected by a centrally disposed vertical spindle or cylindrical staff 8 the same terminating in a bottom screw threaded extension 8' passed through the plate B and provided with a clamping nut 9 below the plate B, and in an upper reduced extension 8'' passed through and terminating flush with the top of the platform 1, the pattern plates being secured to the extension 8'' by screws 10 passed through suitable bosses 11 formed on the bottom of the pattern plates. Similar screws 10 passed through similar bosses 11 likewise secure the pattern plates directly to the platform 1, the front and rear bosses being preferably secured by bolts 12 as shown in Fig. 5, said bolts passing entirely through the platform or table 1. By the construction shown and described the spindle or staff 8 is shouldered to both the members B and 1, the upper end thereof being secured to the pattern plates, the whole resulting in a very strong and rigid construction. Reciprocating vertically on the staff or spindle 8 is a multiple-armed spider 13, the free ends of the several arms projecting slightly beyond the front and rear walls of the platform 1, and under the lugs 7 of the flasks when the latter have been properly deposited on their respective pattern plates (Fig. 3). The outer terminals of the spider arms are provided with split threaded bearings or pinch sockets 14 for receiving the adjustable lifting bolts or screw-pins 15, the pins being adjusted so as to cause their upper ends to touch the bottoms of the lugs 7 of the flasks 3 when the latter have been deposited on their pattern plates. The spider arms converge to a com-

mon hub 16 terminating in a reduced bottom extension or sleeve 16' leaving an outer annular shoulder *w* between the parts, said shoulder being engaged by the plane upper edge of a cam ring 17 passed over and set-screwed to the sleeve 16', the bottom edge of the ring being formed into two wedge cams *e*, to be engaged by corresponding cam formations *e'* formed on the inner terminal 5 edge of a cam-head or hub 18 of a horizontally swinging operating lever 19, the free end of which is provided with a suitable handle *H*. The hub 18 is passed loosely over the sleeve 16' below the cam-ring 17, the bottom of the hub 10 resting on the boss 20 formed on the plate *B*, and being free to rotate about the sleeve 16'. At the same time the spider hub 16 and its sleeve 16' are loose on the staff 8 so as to be free to reciprocate vertically on said 15 staff. To prevent rotary displacement of the spider during these vertical reciprocations, suitable guide pins 21 are rigidly secured to the platform 1 (in the present example shown as passed through openings in 20 the platform and fitting with a drive fit in said openings) on opposite sides of the staff 8, the said pins projecting below the platform and playing loosely in openings 22 formed for their reception in the spider 13. 25 The said pins insure for the spider a rectilinear reciprocating movement at all times, every point in the spider moving in right lines without lateral or rotary displacement. 30

The operation of the machine is substantially as follows: After the sand *s* has been 35 squeezed down by the cope-boards *c* (assuming we are using both flasks) to the level of the upper edges of the flasks, the cope-boards and sand frame *f* are removed (any sand on top of the sprue pins being brushed 40 off the pins with the finger before the cope-boards are applied as fully shown in Fig. 1), the squeezing operation not only compacting the sand, but causing the pattern to be im- 45 pressed in the sand, the design of the pattern (including gates and sprue pin) as im- 50 pressed being shown in Fig. 7. During the sand-squeezing operation it will be under- 55 stood that the flasks 3 are resting on the pattern plates 2, and that the spider 13 is 60 in its lowest position, with the upper ends of the lifting pins 15 touching the bottoms of the lugs 7 of the flasks, and with the 65 guide pins 5 protruding through the perfora- tions formed for their reception in the lugs 4 of said flasks. For this position of the parts, the lever 19 is swung to the right as shown in Fig. 1. As previously pointed out, the drawing of the pattern from the mold is 70 a delicate operation, because unless the separation or parting of these members is at all times and at all points along right lines which are substantially perpendicular to the plane of separation or contact plane between 75 them, there is danger of disarranging the

sand around the mold or impression left in the sand, resulting in a defective mold. As well understood in the art the practice of loosening the pattern by tapping or by a succession of tremors preparatory to drawing is resorted to, especially where the pattern is subsequently drawn by hand. By the use of the present machine however, tapping or vibration of the pattern is entirely dispensed with, particularly in the case of patterns for small castings to the drawing of which the present invention is specially adapted. Assuming the parts to be in their depressed position as described, the operator thereupon swings the lever 19 to the left 80 (through an arc of substantially 135 degrees) causing the cam surfaces *e'* of the boss 18 thereof to ride "down" the corresponding surfaces *e* of the cam ring 17, thereby forcing the said ring against the hub 16 (that is to say, against the shoulder *w* formed by the members 16, 16'), of the spider and lifting the spider. As the spider moves upward the pins 15 thereof lift the flasks 3 whose lugs 7 are engaged by said 90 pins, the flasks being guided, and held to a strict movement of translation by the guide pins 5, the distance to which the flasks are lifted by the swing of the lever 19 being insufficient however to withdraw the guide 95 pins from the lugs 4 of the flasks. The raised positions of the flasks are shown in Fig. 2, the patterns having been fully drawn from the sand of the molds. To remove the flasks from the machine the operator seizes 100 the same by the lugs 4, 4, withdrawing the latter entirely from the pins 5, and with the mold of the pattern pointing downward he deposits the first flask on a suitable support or surface *A* (Fig. 6), all subsequent flasks 105 being then piled on top of the first flask to any required number, two being shown in Fig. 6 by way of example. The molten metal is then poured into the central vertical pas- 110 sage made by the succession of sprue holes *o'*, the metal finding its way through the gates *m'* into the molds *a'* and risers *h'*. The ring castings are then detached from the metal cast in the gates and risers, the narrow neck of metal connecting the cast 115 ring to the metal of the gate and riser being readily broken as obvious from Fig. 6 of the drawings. It will be seen from the fore- 120 going that from the moment the flask 3 starts to lift off the pattern until its upward movement is arrested by the lever 19 reach- 125 ing the limit of its lifting stroke (the sweep of the lever being limited by the front standards *S*, *S*, between which it operates) the flask moves along right lines perpendicu- 130 lar to the plane of separation between the pattern and flask and mold carried thereby, the drawing of the pattern being accomplished by a relative movement of translation between the pattern (or pattern plate)

and the flask and its mold. In the present machine the flask and its mold move and the pattern is stationary or fixed; but it is within the scope of our invention to include 5 machines in which the pattern moves and the flask (with its mold) is stationary, and likewise machines in which both the aforesaid members move. The preferred construction is that herein shown or its equivalent. 10

As well understood in the art, the pattern is usually formed with a draw or taper to permit the ready removal thereof from the mold, the purpose of the draw being to prevent 15 the scraping of the surface of the mold by the pattern as the latter is being drawn therefrom. This scraping is entirely absent by the use of our machine, the rectilinear or translational movement imposed on the reciprocating flask-actuating spider or member of the machine, effecting a clean separation between the draw surfaces of the pattern and mold the instant the drawing operation begins, said separation being maintained 20 throughout the entire operation, a result not attainable by the prevailing methods of drawing the pattern on account of uneven movements, lateral displacements and oscillations of either the pattern or mold taking 25 place in the drawing operation. Since a clean and permanent separation between the pattern and the mold necessarily results from a movement of translation of one of the members (there being no unevenness or unsteadiness in such a movement and no lateral sways or displacements) it follows that with the use of our machine the draw or taper of the pattern may be reduced to a minimum without danger of 30 scraping the sides of the mold, or the rubbing together of the parting draw surfaces of the mold and pattern. By reducing the draw we produce a mold the casting from which requires less machining than is possible 35 under the prevailing practice where considerable draw is necessary to permit the drawing of the pattern previously tapped or subjected to vibration to loosen it from the sand. In the present machine it will be seen 40 that a square flask is employed. It is found in practice that the sand in a square flask lends itself to a more even squeeze than is possible with oblong or other forms of flasks. Obviously the details of the machine may be considerably changed without 45 in any wise affecting the nature or spirit of the invention. In the present machine employing a reciprocating spider for lifting the flask off the pattern, the lever 19 at the conclusion of each operation is necessarily 50 swung to the right (Fig. 1), this causing the cam faces e^7 of the lever hub to ride "up" the inclines e of the cam ring 55 thereby allowing the spider to drop and permit a fresh flask to be deposited on the 60

pattern plate and over the lifting pins 15. The pattern is of course brushed clean at the conclusion of each operation, a matter well understood by those skilled in the art.

Having described our invention what we 70 claim is:

1. In a pattern drawing machine, a fixed support for the pattern, a spindle disposed below and contiguous to said support, a vertically reciprocating member mounted on the spindle, means interposed between the pattern-support and said reciprocating member for guiding the latter, a flask adapted to be positioned over the pattern and engaged by the reciprocating member at points contiguous to the fixed support, said member operating to lift the flask with an upward movement of the member, and means on the support for guiding the flask while being lifted. 75

2. In a pattern drawing machine, a suitable supporting frame, a platform surmounting the same, a spindle depending from the platform, a vertically reciprocating member mounted on the spindle, means for actuating the reciprocating member, a pattern plate on the platform adapted to have deposited thereover a flask with its sand to receive the impression from the pattern, devices on the reciprocating member adjacent the platform operating to engage and lift the flask and its mold with an upward movement of the reciprocating member, and means on the platform for guiding the flask while being lifted. 85

3. In a pattern drawing machine, a fixed support for the pattern, a spindle depending from said support, a vertically reciprocating member mounted on the spindle, means interposed between the pattern-support and said reciprocating member for guiding the latter, a flask adapted to be positioned over the pattern and engaged by the reciprocating member at points contiguous to the fixed support, said member operating to lift the flask with an upward movement of the member, and means on the support for guiding the flask while being lifted. 100

4. In a pattern drawing machine, a fixed support for the pattern, a spindle mounted rigidly below the support, a vertically reciprocating member mounted on the spindle, means independent of the spindle for guiding the reciprocating member, means on the spindle for actuating the reciprocating member, and a flask adapted to be positioned over the pattern and engaged by the reciprocating member, said member operating to lift the flask with an upward movement of the member. 115

5. In a pattern drawing machine, a fixed support for the pattern, a spindle depending from the support, a vertically reciprocating member mounted on the spindle, means interposed between the pattern-support and 120

- reciprocating member for guiding the latter, means on the spindle for actuating the reciprocating member, a flask adapted to be positioned over the pattern and engaged by the reciprocating member at points contiguous to the fixed support, said member operating to lift the flask with an upward movement of the member, and means on the support for guiding the flask while being lifted.
6. In a pattern drawing machine, a suitable supporting frame, a platform or table surmounting the same, a central spindle depending from the table, a vertically reciprocating spider mounted on said spindle, means on the table for guiding the spider in its reciprocations, means for actuating the spider, a pattern plate mounted on the table and adapted to have deposited thereon a flask with its sand to receive the impression from the pattern, pins on the spider engaging the bottom of the flask at different points, and with an upward movement of the spider serving to lift the flask from the pattern along right lines perpendicular to the separating plane between the pattern and mold, and devices on the table for guiding the flask while being lifted.
7. A pattern drawing machine comprising a supporting frame surmounted by a platform or table, a central spindle depending from the platform and having its lower end rigidly secured to the frame, a vertically reciprocating spider comprising a central hub traversing said spindle and arms radiating from the hub, means on the spindle engaging the hub for actuating the spider, the arms of the spider terminating at points beyond the edges of the platform, pins leading upward from the outer ends of the spider arms, means on the platform for guiding the spider and preventing rotary displacement thereof during its reciprocating movements, a pattern plate secured to and surmounting the platform, a flask resting on the pattern plate and provided with marginal lugs projecting beyond the edges of the platform and having their bottoms engaging the upper ends of the pins leading from the ends of the spider arms, pins projecting from the platform and loosely traversing the flask for guiding the flask as the same is lifted by the pins on the spider arms with an upward movement of the spider, the flask in its lift ing movement moving along right lines perpendicular to the parting plane between the flask and pattern plate.
8. In a pattern drawing machine, a stationary frame provided with a pattern-plate supporting platform, a vertical spindle depending from said platform, a spider provided with a central hub terminating in a reduced extension loosely embracing the spindle, a cam ring secured to the extension and shouldered against the offset formed between the hub and the extension, an operating lever terminating in an annular cam head or hub loosely embracing the reduced extension of the spider hub below the cam ring and engaging said ring whereby with a sweep of the lever in a given direction the play of the cam surfaces over one another will lift the spider, the latter in turn operating to lift a flask deposited over the pattern plate, whereby the separation between the pattern and the mold in the flask will take place along right lines perpendicular to the plane of separation between the pattern plate and flask and its mold.
9. In a pattern drawing machine, a fixed support for the pattern, a centrally disposed spindle mounted below and contiguous to the support, a vertically reciprocating member on the spindle, and means on the member for engaging and lifting a flask deposited over the pattern.
10. In a pattern drawing machine, a fixed support for the pattern, a centrally disposed spindle mounted below and contiguous to the support, a vertically reciprocating member on the spindle, devices on said member contiguous to the support operating to engage and lift a flask deposited over the pattern, and means for guiding the flask while being lifted.
11. In a pattern drawing machine, a fixed support for the pattern, a staff disposed below and contiguous to the support, a vertically reciprocating member on the staff, and means on the member for engaging and lifting a flask deposited over the pattern.
- In testimony whereof we have hereto affixed our signatures respectively the 14th day of September, 1918, and the 19th day of September, 1918.
- HERBERT H. CUMMINGS.
ARDEN J. MUMMERT.
